CARBURETOR

Emil O. Wirth, South Bend, Ind., assignor to
 Bendix Aviation Corporation, South Bend, Ind.,
 a corporation of Delaware

Application December 27, 1943, Serial No. 515,727

8 Claims. (Cl. 261—69)

1

This invention relates to fuel feeding systems for internal combustion engines and more particularly to mixture control and fuel cut-off devices for systems of this character which are generally used on aircraft and in which liquid fuel is supplied to the engine under superatmospheric pressure and is metered while being maintained under pressure.

Some fuel systems of the foregoing character include a manual mixture control device for varying the richness of the mixture and means for cutting off the flow of fuel to the engine. In such systems it is known to arrange the manual mixture control device and fuel cut-off valves so that actuation of the mixture control valve may effect actuation of the fuel cut-off valve. However, it is not always desirable to actuate both valves solely by the same actuating means for under some circumstances it may be desirable to cut off the fuel flow to the engine without altering the position of the valve of the mixture control device and it is therefore an important object of the present invention to provide means whereby the fuel cut-off valve may be closed without affecting the position of the valve of the mixture control device, as well as providing means whereby both valves may be actuated together.

Another object of the invention is to provide a device of this character wherein the mixture control valve may be adjusted independently of the cut-off valve.

Still another object of the invention is to provide a device of this character wherein the means for actuating the cut-off valve, independently of the mixture control valve, is effected by electrically operated means.

It is a further object of the invention to provide a device of this character wherein electrical means for independently controlling the cut-off valve is operated in connection with the ignition switch of the engine. This is desirable as it reduces the number of switches and the like which the operator must actuate in starting and stopping the engine and the arrangement has a further advantage in that both the fuel supply and ignition are cut off simultaneously.

A still further object of the invention is to provide a device of this character wherein novel improvements reside in certain details of construction, arrangement, and combinations of the parts.

Another object of the invention is to provide a simplified device of this character which may be built at reasonable cost and which is accurate and reliable in operation.

2

Other objects and advantages of the invention will be readily apparent to those skilled in the art from the following description taken in connection with the accompanying drawings, which represent a preferred embodiment. After considering this embodiment skilled persons will understand that many variations may be made without departing from the principles disclosed; and I contemplate the employment of any structures, arrangements, or modes of operation that are properly within the scope of the appended claims.

In the drawings:

Figure 1 is a diagrammatic sectional view of a fuel feeding system embodying the present invention; and

Figure 2 is a partial section of same showing a modification of the invention.

With reference to Figure 1, there is shown a main body member 10 which contains an induction passage 12 therethrough having an air inlet 14 and an outlet 16, the air inlet being provided with an outer surface 18 to which an air scoop (not shown) opening in the direction of travel may be secured and the outlet 16 being provided with flanges (not shown) for securing the body member 10 to the manifold of an internal combustion engine or to the inlet of a supercharger if one is used between the carburetor and the manifold. If desired, a supercharger may be used anterior to the body member 10 either in place of or in addition to a supercharger posterior to said body member. A venturi 20 having separable inlet and outlet sections is positioned in the induction passage adjacent the inlet 14 and is formed with an annular chamber 22 which communicates with the interior of the venturi through an annular slot 24 to be thereby subjected to Venturi depression. An annular chamber 26 is in free communication with the air entering the venturi through an annular opening 28, the opening 28 being preferably subjected to the impact pressure of the air supplied to the venturi. A throttle 30 is pivotally mounted in the induction passage posterior to the venturi and is adapted to be manually actuated to control the air flow to the engine.

The fuel flow to the engine is regulated or controlled by an unmetered fuel pressure control unit or regulator, indicated generally at 32, which regulates or determines the fuel pressure on the upstream side of a fuel metering jet system diagrammatically illustrated as jet or orifice 34 and by a discharge nozzle assembly indicated generally at 36 which regulates or determines the

pressure on the downstream side of the metering orifice 34. It will be understood that the metering jet system 34 might consist of some other arrangement than that above described such as any well known conventional system of jets wherein the effective fuel metering area is varied to provide power enrichment, idling or running mixture richness control, or altitude richness control.

The interior of the regulator unit 32 is divided into three chambers 40, 42 and 44 by diaphragms 46 and 48. As shown the diaphragms 46 and 48 have an area ratio of one-half although, as will be apparent hereinafter, any desired area ratio may be used. The center portions of the diaphragms are supported by thin plates 50 between which the diaphragms are clamped by centrally disposed rivets 52 and 54 under the deformed ends of which washers 56 may be provided so that the thin plates will not tear loose from the riveted-over portion of the rivets. The rivet 52 is provided with a cylindrical recess and rivet 54 is provided with a shank 55, one end of which is freely received in the recess of the rivet 52, said end of shank 55 being preferably rounded to form an angularly adjustable one-way connection with the diaphragm 36 whereby slight misalignment of said diaphragms may be accommodated without binding. This construction also greatly facilitates assembly and disassembly of the control unit 32.

Chamber 40 is provided with a fuel inlet port controlled by a valve 60 and receives fuel from a source of fuel under pressure, such as a fuel pump (not shown), through a pipe 62. The valve 60 has a pin-like extension projecting into the chamber 40 in position to be engaged by the head of rivet 52 whereby movement of the diaphragms to the right, as shown by the drawing, opens the valve. A spring 64 urges the valve toward its closed position. A spring 66 is mounted at one end in the chamber 44 and has its free end received in a spring retainer portion of a lever 68 pivotally mounted at one end and having a crimped center portion normally engaging the head of rivet 54 and urging the diaphragms to the right in a direction to open the valve 60. The spring 66 may be rendered inoperative, when the engine is to be stopped, by a plunger 70 which upon downward movement thereof engages the free end of lever 68 and moves the lever to the left against the force of spring 66. The lever 68 will thus move out of engagement with the rivet 54 whereby the fuel pressure in chamber 40 will move the diaphragm 46 to the left and permit the spring 64 to close the valve 60 and cut off the fuel supply to the engine. In order to eliminate vapor, a pipe 72 having a restricted communication 73 with the top of chamber 40 may be provided, said pipe leading back to the fuel supply tank.

The chamber 42 of the regulator unit 32 is connected to the Venturi annulus 22 by means of pipes 75, 82 and a passage 76 in the body 10, and is therefore subjected to a pressure primarily derived from the throat of the venturi 20. A restriction 78 may be provided in passage 76 if desired. The chamber 42 is also connected to the air scoop or Venturi entrance by means of a calibrated passage 80, controlled by a manual mixture control valve 82, a passage 84, the annular chamber 26 and annular opening 28. The chamber 44 of the regulator unit 32 is connected to the annular Venturi entrance chamber 26 by a branch passage 85 of the passage 84 and is

therefore subjected to a pressure primarily derived from the Venturi entrance. A restriction 86 may, if desired, be provided in the passage 84. The chamber 44 is also connected to the Venturi annulus 22 through passages 90, 92, 75 and 76, the communication between passages 90 and 92 being controlled by a valve 94 of an automatic mixture control unit indicated generally at 96, the valve 94 being connected with and movable by a bellows 97 which is responsive to variations in barometric pressure. Unmetered fuel entering the chamber 40 of the regulator from the fuel inlet 62 passes through the fuel metering jet system diagrammatically illustrated by the metering orifice 34, thus becoming metered fuel which is transmitted through a pipe 98 to a chamber 104 of the discharge nozzle assembly 36. The chamber 104 of the nozzle assembly 36 is separated from a chamber 150 by a preformed annularly grooved diaphragm 152 connected to a fuel outlet valve 154 which is urged to the right, in a direction to close the valve, by a spring 156 arranged to be variably loaded by an adjustment screw 158, said chamber 150 being connected to the Venturi annulus 22 by the passage 76. The stem of valve 154 is of triangular cross section or otherwise relieved to permit fuel flow thereto past a fuel discharge nozzle indicated generally at 159 and is slidable within a nozzle bar 160 of the nozzle 150. In this arrangement the valve 154 is not fixed to the diaphragm 152 but is maintained in abutting relation therewith by means of a light spring 162 which constantly urges the valve 154 to the left. This arrangement eliminates any tendency for the valve to bind in its valve guide and seat member 164 as a result of misalignment between the diaphragm and the guide member.

The calibrated passage 80 interconnects the chambers 42 and 44 and is controlled by the mixture control valve 82 which is urged in the closed direction by a spring 166. Valve 82 may be independently adjusted as desired from the pilot's compartment by a cable actuated member 168. A cable (not shown) is connected to the member 168 and said cable leads to the pilot's compartment where it is attached to a cable actuating device (not shown) of any well known character whereby actuation of the cable will effect corresponding movement of the valve 82. This adjustment is manually effected and provides the pilot with means for manually regulating the richness of the fuel mixture to meet the requirements of the engine under various operating conditions. The stem of said valve 82 is provided with a conical collar 170 which is adapted to engage a pivoted lever 172 to force the plunger 70 downwardly when the mixture control valve is moved beyond its wide open or lean position to its idle cut-off position for effecting closing of valve 60 to cut off the fuel flow to the engine. Means for effecting closing of the fuel valve 60, independently of the valve 82, comprises a solenoid 180 which has an axial bore within which a plunger 184 is slidable. The plunger 184 has an extension 186 connected with lever 172 adjacent the upper end thereof, there being a stop 188 for limiting movement of the plunger 184 to the left as viewed in the drawing. The solenoid is adapted to be energized by electric current from a suitable source of supply such as a storage battery 190 or other electrical supply means. A switch 192, for controlling said current, is provided in wire 194, said switch prefer-

ably being located conveniently in the pilot's compartment of the aircraft.

Operation

The operation of the device is as follows:

Assuming the carburetor has not been filled with fuel and the idle cut-off plunger 70 is in its upward position as shown, the spring 66 will urge the diaphragms to the right and open the valve 60. Fuel under pressure supplied to pipe 62 enters and fills chamber 40 and flows through the jet 34 and pipe 88 to the chamber 104. As the pressure in chamber 40 increases it acts against the diaphragm 46 and tends to compress spring 66 whereby the valve 60 tends to close. Fuel under pressure supplied to chamber 104 acts on diaphragm 152 and tends to open valve 154. The screw 158 is normally adjusted to compress spring 156 to such a point that a slightly lower pressure is required in chamber 104 to open the valve 154 than is required in chamber 40 for sufficiently compressing the spring 66 to permit the valve 60 to close. Once the carburetor has been fully filled with fuel, fuel will therefore slowly spill from the discharge groove 161 of the fuel nozzle, unless the lever 68 is actuated by forcing the plunger 70 downwardly and compressing spring 66 so as to allow valve 60 to close. Although the screw 158 has been described as being adjusted to permit valve 154 to open at a pressure somewhat less than the closing pressure for valve 60, it will be apparent that by screwing the adjustment screw 158 in or out the pressure in chamber 104 required to open valve 154 may be made greater than, equal to or less than the pressure required in chamber 40 to permit the valve 60 to close. It will also be apparent that the actual value or degree of the fuel pressures will be determined by the strength of the springs 66 and 156, the pressure required being greater as the strength of the springs is increased.

During operation, assuming the area ratio of the diaphragms 48 and 46 is equal to two, the regulator unit 32 functions to maintain a differential fuel pressure across the metering unit 34 which is equal to twice the venturi to entrance air differential pressure. For example, a given decrease in the pressure in the Venturi chamber 22 is transmitted to the chamber 42, where it results in an equal increment increase in the unmetered fuel pressure in chamber 40, and is transmitted to chamber 104, where it results in an equal increment decrease in the metered fuel pressure. Consequently the fuel metering differential pressure is increased in amount double the increase in the air differential. Similarly a given increase in the entering air pressure in the chamber 26 is transmitted to chamber 44 and since it is applied to the diaphragm 48 having twice the area of diaphragm 46, the unmetered fuel pressure in chamber 40 is increased an increment double the increase in entering air pressure.

Although the diaphragms 48 and 46 are shown as having a two-to-one area relationship, they may be of any other desired area ratio, in which case the fuel metering differential pressure will be maintained at some multiple, other than two, of the air differential pressure. For example, if the area of diaphragm 48 is three times the area of diaphragm 46, the fuel differential will be maintained equal to three times the air metering differential. Or, if diaphragms 46 and 48 are of equal size, the fuel metering differential pressure is maintained substantially equal to the air differential pressure. In any event, the fuel and

air differential pressures are maintained in constant proportion and therefore constant fuel to air proportioning is obtained.

The automatic mixture control unit 96, or altitude control unit, as it is sometimes referred to, is provided to maintain a constant mixture richness with variations in altitude. Upon a decrease in the density of the air entering the venturi, as by increase in altitude, the differential 10 between the entering air and the Venturi pressures will increase for a constant weight of air flow per unit of time and will tend to increase the fuel flow and enrich the mixture. As the density increases, however, the bellows 97 expands, because of a decreased pressure on the exterior of the bellows, and moves valve 94 downwardly to increase the area of communication between the pipes 90 and 82. Air is thus bled into the chamber 42 to thereby reduce the differential pressure which would otherwise exist between the chambers 42 and 44, whereby unmetered fuel pressure in chamber 40 is increasingly decreased. By properly contouring the valve 94, the differential in the air pressures in chambers 42 and 44 are 20 so controlled that the fuel supplied to the engine remains constant for a given weight of air flow per unit of time even though the entering air density changes. Automatic altitude compensation is thus obtained.

30 It is generally considered desirable in carburetors of this character to provide the pilot with a manual mixture control so that he can manually regulate or vary the richness of the mixture between predetermined limits to provide the proper fuel mixture required by the engine under various operating conditions. Such regulation of the mixture is effected by the valve 82 which controls the calibrated passage 80 and said valve 82 is adjustable from a position whereat the passage 80 is completely closed to a position whereat passage 80 is fully open. A rich setting is effected by closing the valve 82 and as said valve is opened air is bled from the air scoop chamber 44 into the Venturi chamber 42 whereby the differential pressure between these chambers is reduced 35 an amount depending upon the extent the valve 82 is opened. This in turn reduces the unmetered fuel pressure in chamber 40 to maintain the diaphragm assembly in an equilibrium position, thus 40 reducing the fuel metering differential and consequently reducing the richness of the mixture for a given air flow. With the valve 82 completely withdrawn the carburetor is in its full lean position, the effective area of passage 80, as limited 45 by the seat of valve 82, determining the maximum permissible bleeding action. The manual mixture control valve 82 and the automatic mixture control unit 96 control the pressures in the chambers 42 and 44 and also have some effect 50 on the pressure in the chamber 150 of the valve assembly unit 36.

When the engine is to be stopped it is desirable to cut off all fuel flow thereto so that it will not continue to run, as a result of pre-ignition, after 55 the ignition is turned off. To accomplish this end, the valve 82 is moved upwardly beyond its full lean position to an idle cut-off position at which the plunger 70 is forced downwardly, by the action of collar 170 on lever 172, whereby lever 68 is forced to the left and the spring 66 is compressed and the light spring 64 is able to fully close valve 60.

As pointed out above it may be desirable, under certain conditions, to cut off the fuel flow to the 70 engine without altering the position of the valve

82, as when said valve 82 is adjusted for some particular operating condition and it is desired to retain this adjustment so that the fuel mixture will be the same when the engine is restarted as when it was stopped. Under such conditions the fuel may be cut off by closing switch 192 of the solenoid circuit thereby effecting actuation of the lever 172 to force plunger 70 downwardly thereby compressing spring 68 and effecting closing of valve 60 as above described.

If desired the solenoid controlling the fuel cut-off valve may be controlled simultaneously with the ignition switch as shown in Figure 2 wherein the solenoid 180 is controlled by ignition switch 210 so that when said switch is closed the solenoid is energized and when the switch is opened the solenoid is deenergized. The solenoid plunger 212 is connected with the lever 172 by a rod 214. A relatively heavy spring 216, disposed about the rod 214, reacts between a fixed member 218 and a member 220 secured to said rod, said spring being adapted to urge the rod to the left in a direction which will effect movement of the upper end of the lever 68 to the left and permit closing of the cut-off valve 60 by spring 64. It is to be noted that the spring 216 is of sufficient strength to overcome the force of spring 68.

Normally when the solenoid 180 is deenergized spring 216 urges rod 214 to the left until member 220 abuts against portion 222 of the solenoid assembly at which time lever 68 is moved to a position which will permit valve 60 to close. Upon closing of the ignition switch 210 the solenoid is energized and moves plunger 212 to the right against the force of spring 216 until the lower end of lever 172 engages stop 224. Spring 68 then is freed to effect opening of valve 60.

Should it be desired to effect closing of valve 60 when the solenoid is energized the mixture control valve 82 is moved upwardly until the conical collar 170 engages the upper end of lever 172 and actuates said lever in the manner hereinabove described in connection with Figure 1, it being understood of course that valve 82 may be moved from its fully closed to its fully open position without effecting actuation of lever 172. Thus it will be apparent that in both embodiments of the invention the mixture control valve 82 may be moved throughout its effective range as a valve without effecting the position of the cut-off valve 60. Further both the manual mixture control valve 82 and the valve 60 may be controlled simultaneously, and the cut-off valve 60 may be independently controlled without effecting the position of the mixture control valve 82.

From the foregoing it will be understood that many changes may be made in the form and arrangement of the parts of the present invention without departing from the spirit and scope thereof or sacrificing all of its material advantages and it is not intended that the scope of the invention shall be limited to the form shown and described nor otherwise than by the terms of the appended claims.

I claim:

1. In a fuel supply system for internal combustion engines: an air supply passage; a fuel supply conduit; a cut-off valve controlling said conduit; means including a mixture control valve for controlling the richness of the fuel mixture delivered to the engine; means so constructed and arranged to control both of said valves; and electrically operated means adapted to control the first mentioned valve independently of the means for controlling both valves.

2. In a fuel supply system for internal combustion engines wherein the fuel is supplied to the engine under super-atmospheric pressure and is metered while being maintained under pressure; a fuel conduit having metering means therein; a fuel cut-off valve which when closed prevents fuel from flowing through said conduit to the engine; a mixture control valve for controlling the richness of the fuel mixture delivered to the engine; means so constructed and arranged as to control both said valves; and means adapted to control the first mentioned valve independently of the means for actuating both of said valves.

3. The invention defined by claim 2 wherein the means for controlling both of said valves is manually operated and the means for controlling the cut-off valve is electrically operated.

4. The invention defined by claim 2 wherein the means for controlling the cut-off valve independently of the means for controlling both of said valves includes an electrically operated solenoid.

5. In a fuel feeding system for internal combustion engines in which liquid fuel is supplied to the engine under superatmospheric pressure and is metered while being maintained under pressure: means for regulating the unmetered fuel pressure; means for regulating the metered fuel pressure independently of the means for regulating the unmetered fuel pressure; a fuel cut-off valve; means including a valve for modifying the richness of the fuel mixture delivered to the engine; means for simultaneously controlling both of said valves; and electrically operated means for controlling the cut-off valve independently of the second mentioned valve.

6. In a charge forming device: an air passage; a venturi therein; a throttle valve in the passage posterior to the venturi; a fuel conduit; a metering restriction in the conduit; means including a valve in the conduit anterior to the restriction and a pair of diaphragms urged in the opposite directions by the pressure in the air passage, the air supply pressure and by unmetered fuel pressure; means for controlling only the unmetered fuel pressure; means including a valve in the conduit posterior to the restriction and a diaphragm urged in opposite directions by the pressure at the venturi and by metered fuel pressure for controlling only the metered fuel pressure; means including a mixture control valve for controlling the richness of the fuel mixture delivered to the engine; manual means for controlling the first mentioned valve and the mixture control valve; electrically actuated means for controlling the first mentioned valve independently of the mixture control valve; and a valve operated automatically in response to variations in pressure resulting from variations in altitude for controlling the richness of the mixture delivered to the engine.

7. In a fuel supply system for internal combustion engines wherein the fuel is supplied to the engine under super-atmospheric pressure and is metered while being maintained under pressure: a fuel conduit having metering means therein, a valve for controlling the richness of the fuel mixture delivered to the engine; a fuel cut-off valve which when closed prevents flow of fuel through said conduit; means so constructed and arranged that the first mentioned valve may be independently adjusted and the cut-off valve is actuated when said means is adjacent one limit of movement; and means adapted to control the

fuel cut-off valve independently of the first mentioned means.

8. In a fuel supply system for an internal combustion engine wherein the fuel is supplied to the engine under super-atmospheric pressure and is metered while being maintained under pressure; a fuel conduit having metering means therein, a mixture control valve for controlling the richness of the fuel mixture delivered to the engine; a fuel cut-off valve in said conduit; a member on the mixture control valve; means adapted to be actuated by said member only when the mixture control valve has been substantially fully opened for effecting closing of the fuel cut-off valve; and means adapted to close the fuel cut-off valve independently of the first mentioned means when the mixture control valve is in a less open position than that whereat the member thereon will effect closing of the cut-off valve.
